UNITED STATES PATENT OFFICE.

EDWIN J. OXFORD AND JAMES PETR, OF CHAMBERS, NEBRASKA.

EMERGENCY JACK.

Application filed October 17, 1922. Serial No. 595,089.

To all whom it may concern:

Be it known that we, EDWIN J. OXFORD and JAMES PETR, citizens of the United States, residing at Chambers, in the county of Holt 5 and State of Nebraska, have invented certain new and useful Improvements in an Emergency Jack; and we do hereby declare the following to be a full, clear, and exact description of the invention, such as will enable 10 others skilled in the art to which it appertains to make and use the same.

This invention relates to a jack.

One object is to provide a general purpose tool or mechanism of this character adapted 15 to particularly engage an object adjacent to its base rather than at the top as in present structures, in order to raise the object to the maximum height and thus particularly be useful as an emergency jack for raising automobiles or other vehicles when their wheels 20 are stalled in mud, sand or otherwise.

A second object is to provide a novel construction whereby maximum leverage for its operation is attained.

25 Another object is to provide a construction having a novel pawl which is automatically operable or movable to a locking position and which is adapted to be actuated manually or by means of pedal mechanism as preferred.

It is further aimed to provide the novel and generally improved construction which will be hereinafter described in connection with accompanying drawings illustrating an operative embodiment thereof.

35 In said drawings:—

Figure 1 is a side elevation of the improved jack shown in full lines in a normal position and with the lifting member thereof suggested by dotted lines in a raised position;

40 Figure 2 is a view of the jack in edge-elevation taken at a right angle to Figure 1;

Figure 3 is a view of the jack in edge elevation opposite to Figure 2;

45 Figure 4 is a top or plan view;

Figure 5 is a detail perspective view of the lifting member alone;

Figure 6 is a detail perspective view of the standard alone;

50 Figure 7 is a detail perspective view of the pawl alone;

Figure 8 is a detail perspective view of a portion of the lifting member showing an extension in place on the lug thereof; and

55 Figure 9 is a detail perspective view, frag-

mentary, of said lifting member, showing a chain securing element in place thereon.

Like reference characters designate like or similar parts in the different views.

In carrying out the invention, a standard 60 is provided which is generally designated A and which may have spaced upright bars 10 preferably of metal and integral with each other and joined by a longitudinal bridge at the front edge as at 11 and at the 65 top and at the rear edge by a bridge 12. Uprights 10 have laterally extending attaching flanges 13 at their lower ends and secured as by means of rivets 14 to a relatively wide metallic or other supporting base 15.

70 Slidable longitudinally of the standard A between the uprights 10 is a lifting bar 16, preferably of metal, which is disposed intermediate the bridges 11 and 12 as shown. Bar 16 is adapted to be lifted by a suitable mechanism and to this end is provided with alternate teeth and notches 17 and 18, preferably of the specific shape and example shown. They may differ however as is obvious.

75 A pawl is provided having horizontal pin 80 19, a stud 20 and an offset manipulating finger at 21. Opposite to bridge 12, the uprights 10 are extended to provide ears 22 between which the stud 20 is disposed and to which the same is pivoted by means of a pin 85 at 23. The pawl is thus arranged so that the pin 19 will always move by gravity toward the lifting member 16 and thus seek a position in the adjacent notch 18.

80 The pawl pin 19 thus serves to permit movement of the lifting member 16 and to hold the same in adjusted positions.

Said lifting member 16 may engage the object to be lifted at its upper end and be suitably shaped thereat to accommodate the same, for instance by the provision of a notch 95 at 24. It is preferred however that the lifting member 16 engage the object adjacent the base 15 and to this end has a laterally extending lug 25 which projects through and beyond the base or opening at the rear of the uprights 10. Lug 25 is integral with the lifting member 16 and its upper edge is secured in a horizontal plane. A vertically disposed hole or aperture 26 is provided 100 through the lug 25 and a stud 27 is normally disposed therein, extending from a shoe 28 resting on the lug 25 and being broader than the same and adapted to directly engage the object to be lifted. The stud 27 is removably 105 110

secured in place as by means of a cotter pin 29 passing through an opening 30 in stud 27.

Instead of having the notch 24 engage the object to be lifted, a head or cap 24^a consisting of the bifurcated shank 24^b and the flat head 24^c may be employed. The upper surface of the head 24^c is roughened as shown and the bifurcated shank 24^b has its legs disposed one on each side of the lifting member 16 and is secured thereto in any suitable manner as by a cotter key 24^d passing through openings in the shank 24^b and through an opening 24^e in the upper end of the lifting member. The head or cap 24^a is partly received by the notch and is maintained against lateral movement by the same. The flat head 24^c presents a relatively large surface on which the object to be lifted may rest, and the same being roughened as shown serves to prevent accidental relative movement between the head and the object engaged.

Instead of the shoe 28, an extension shoe 31 of any suitable shape may be placed on the lug 25 as shown in Figure 8 preferably being serrated or otherwise roughened as at 32 where it engages the object to be lifted and being fastened to the lug 25 in any suitable manner as by means of the removable bolt 33.

Still further, instead of the shoes or extensions 28 or 31, a chain securing post 34 may be used. This post preferably has a conical head 35 and a depending securing shank 36 which extends into the hole 26 and which may be loosely placed therein as shown or have a cotter pin such as 30 passed therethrough below the lug 25 if desired.

In order to raise and lower the lifting member, a rod or lever 37 is provided having a pivot at 38 passing therethrough and connected to links 39 in turn pivoted on the pin 23. The inner end of the lever 37 extends beyond the pivot 38 and is recessed at 40 so as to provide a nose at 41 adapted to directly engage the teeth 17 after entering the recesses 17.

Instead of manually operating the pawl pin 19 through manipulation of finger 21, a foot operated means may be employed having an elongated link 42 provided with an enlarged opening 43 at its upper end which may be readily passed over or removed from the finger 21 and pin 19. At its lower end, link 42 is pivoted at 44 to a lever 45 pivoted at 46 to the standard A at one of the uprights 10 and the free end of which lever is shaped into a pedal at 47.

In operation, with the lifting element 16 in engagement with the object at the recess 24 or lug 25, lever 37 is rocked on its pivot 38 and successively brought into the recesses 18 so that its nose 41 will engage the teeth 18 and thus by a step by step movement elevate the lifting member 16. In the mean-

time, as the lifting member 16 elevates, the teeth 17 will displace the pin 19 so that it will fall automatically from one recess 18 to the next lowered recess 18, thus holding the lifting member in the position to which it is raised or adjusted. Particular attention is called to the fact that due to this lever mechanism, maximum leverage may be attained.

In emergency cases, for instance where a vehicle is stalled, the lug 25 is engaged with the object to be lifted, for instance the axle or hub extension of the wheel, either directly or with the shoe 28 or 31 in place as preferred since the object may thus be engaged at a considerable distance below the fulcrum of the lever 37 and adjacent the base of the device, enabling the object to be raised to the maximum extent and from the base of the jack as contrasted with the engagement of an object in the upper end of the lifting member. The pawl 21 may be manually operated by means of the finger 21 when desired, for instance to hold the pin 19 out of the path of movement of the lifting member so as to enable the same to rapidly lower. The same result may be accomplished by manipulating the pedal 47 which rocks lever 45, link 42 and finger 21.

When the jack is used for pulling fence posts or the like a chain may be passed about the post and have its end links entered by the head 35 of stud 34, or the chain may, after being secured to the post, be looped about the head 35, in the manner clearly illustrated in Figure 9 of the drawings. As the head is conical, the chain will be drawn or tightened about the post as the stud extends into the end links.

It is to be understood that no limitation as to the use of the device for raising automobiles is to be inferred since it is capable of use broadly, for instance as a wire stretcher, a post puller, a well-pipe puller, a hay press jack, a hay rack jack, a rim expanding and contracting jack and a "house-moving" jack. It will also be understood that various changes in the details of construction, combination and arrangement of the parts may be resorted to provided the same fall within the spirit and scope of the invention.

I claim as my invention:

1. A jack having a standard provided with spaced uprights forming a slot open at one side of the standard, a lifting member operable between the uprights, said lifting member having an object-engaging means extending through and beyond said slot, a bridge integral with and connecting said uprights above the slot, ears integral with and extending from the uprights substantially opposite said bridge, a pawl to coact with the lifting member, a pin pivotally securing said pawl to said ears, links depending from

said pin, an operating finger and a stud integral with said pawl, said operating finger and said stud extending in opposite directions, said stud being pivoted on said pin intermediate said links, an operating lever pivoted to said links, and said standard being cut away below the ears to facilitate engagement of said lever with said lifting member.

2. A jack having a standard provided with spaced uprights forming a slot open at one side thereof, a base, said uprights having outwardly extending flanges integral therewith and attached to said base, a bridge integral with and connecting said uprights above the slot, a lifting member operable between the uprights having object engaging means extending through and beyond said slot, ears integral with and extending from the uprights substantially opposite said bridge, a pawl having a pin to coact with the lifting member, a manipulating finger inter-

gral with said pawl, a stud integral with said pawl, said finger and stud being at opposite ends of said pin and extending on opposite sides thereof, a pin pivotally securing said stud to said ears, links depending from said second mentioned pin, an operating lever pivoted to said links, said standard being cut away below the ears to facilitate engagement of said lever with said lifting member, a link disposed at one side of the standard and connected to said first mentioned pin, and a pedal lever pivoted to said standard adjacent its base and operatively connected to said last mentioned link.

In testimony whereof we affix our signatures in presence of two witnesses.

EDWIN J. OXFORD.
JAMES PETR.
